MARKER FOR BLACKBOARDS

Paul E. Whittington, Arlington, Va.

Application November 14, 1949, Serial No. 127,212

12 Claims. (Cl. 33—86)

(Granted under Title 35, U. S. Code (1952),
sec. 266)

1

The invention described herein, if patented, may be manufactured and used by or for the Government for governmental purposes without the payment to me of any royalty thereon.

This invention relates to devices for marking blackboards and the like with chalk lines.

In the Allen Patent No. 253,490, dated February 14, 1882, a device is shown for marking cloth, etc., with a plurality of equally or unequally spaced parallel chalk lines. My invention employs an open frame having a number of parallel chalked cords or strings, as in the Allen patent, but is an improvement in the following particulars, among others:

1. The marker frame and cords may be manipulated to provide not only equal spacing of the cords but also logarithmic spacing, and "probability" spacing, and combinations of these spacings.

2. The marker frame may be disassembled after the cords are removed to facilitate packing in a small space for storage or shipment.

The invention has other advantageous features as will be apparent from the following description of the preferred embodiment thereof and certain modifications, in connection with the accompanying drawings forming a part of this specification.

In said drawings,

Fig. 1 is a plan view of the device shown with the cords arranged for two logarithmic spacings or scales;

Fig. 2 is a plan view of one corner of the device, on an enlarged scale;

Fig. 3 is a cross section on line 3—3 of Fig. 2 but on a still larger scale;

Fig. 4 is an elevation of one of the corner pieces, on the scale of Fig. 3;

Fig. 5 is a cross section on line 5—5 of Fig. 2, on the scale of Fig. 3;

Fig. 6 is a detail in elevation showing the engagement of one end of a chalking cord with the frame;

Fig. 7 is a plan view of the device of Fig. 1 but shown arranged to make two sets of parallel lines at right angles;

Fig. 8 is detail in cross section of a slight modification;

Fig. 9 is a detail in cross section of another modification;

Fig. 10 is a detail plan view of still another modification; and

Fig. 11 is a detail in cross section showing how the cord end is held by the form of Fig. 10.

Referring particularly to the drawings, and

2

first to Figs. 1-5, the preferred form of blackboard marker consists of a four-sided open frame 15 which is preferably square, being made up of four channel pieces 16, 17, 18, 19 and four like corner pieces 20, all preferably made of stainless steel or other non-corroding metal. Secured to the frame under tension by means to be described are a plurality of chalking strings or cords 21 which when coated with ordinary chalk may be snapped individually by the fingers of the operator against a blackboard or other surface to make lines thereon having the desired spacing. The corner pieces are each angular or L-shaped, with two equal legs having reduced ends 22, 23 which may be square in cross section, as shown, but in any case will be properly shaped and dimensioned to permit endwise insertion and snug fitting in the ends of the channel members, so that each pair of adjacent channel members are held together at right angles by a single corner piece. Shoulders 24 on each leg limit the inward movement of the corner piece relative to the channel with which it is being assembled. The construction is such that the two outer plane surfaces of each corner piece 20 are flush with the respective outer surfaces of the two frame members which are held together by each corner piece, as shown in Figs. 1 and 2. As the form of Figs. 1-5 employs corner pieces square in cross section fitting square channels, it is also possible to insert the corner members by pushing them laterally into the spaces between the flanges of each channel. However the corner pieces are inserted, they must fit snugly enough (in the form of Figs. 1-5) to be held securely by friction. Then the four channel members will be held together in the same plane without likelihood of separating when the device is in use. The channel members are rigid but have sufficient "spring" to permit the slight separation necessary to permit the last corner piece to be inserted after three corner pieces are in position.

Instead of the corner pieces being held by friction alone, which requires careful finishing of the abutting surfaces, positive locking means may be employed, for example the bolt 25 and wing nut 26 of Fig. 9. There will be one bolt 25 passed through each reduced end 22, 23 of each corner piece. This form has the advantage of a secure fastening at each of the corners of the frame, but requires the removal and replacement of eight wing nuts each time any change is made in the relative positions of the frame components. In the form of Fig. 8, the channel flanges have inturned wings 27 which hold the corner pieces

more securely but compel insertion of the corner pieces to be by endwise movement only.

With the frame assembled, the chalking strings or cords 21 are secured according to the desired pattern. Each cord 21 has a knot 28 at each end and after being passed under a channel it is slipped through notches 29, 30 (to be described) cut in the upper or outer edges of the flanges of the several channels (as will be understood from Figs. 5 and 6) and the knot is located in back of the notch as shown. The knots are of course spaced apart so as to insure the requisite tension in the cords when secured to the frame at both ends. In the form of Figs. 10 and 11, the cord 21 is passed through a triangular centering aperture 31 punched in the bottom wall 32 of the channel and then is brought up into engagement with notch 30 on the inner flange of the channel. This form is advantageous in that the cords are centered relative to the notches into which they are moved; also the converging walls of the V of each triangular aperture 31 act to grip the cord by friction and hold it while the cord is slipped into the notch, which is a convenience in assembling cords stretched taut. It is, however, more difficult to thread the knotted cords through the apertures 31 than merely to pass them around the outside walls of a channel.

Referring to Fig. 1, the notches 29 in the outer flange of channel 16 and notches 33 in the outer flange of the opposite channel 19 have exactly the same spacing along the channels, this spacing being a double logarithmic arrangement. When cords 21 are secured in all the notches 29, 33 as shown, and then are chalked, the frame may be held against a blackboard and the cords individually plucked or snapped to mark the blackboard with a set of logarithmic co-ordinates. It will then be easy for the user to draw a logarithmic curve on the board without taking time during a lecture to make measurements, which would cause loss of attention on the part of the auditors.

Still referring to Fig. 1, the inner flange of channel 16 and the corresponding flange of channel 19 are both provided with notches 30, 35 spaced in a single logarithmic series. To employ these notches the frame is taken apart and then channels 16 and 19 are reversed end for end to bring the inner flanges of Fig. 1 outermost. If the construction of Figs. 10 and 11 is used, however, it is possible to space the cords according to the spacing of the inner notches without disassembling the device and reassembling it, since a cord may be secured as desired without alteration of the frame. This will be understood by examining Fig. 11.

The other two channels 17, 18 have notches 36, 37 respectively cut equal distances apart, say one inch, along the outer flanges. Also channels 17, 18 have notches 38, 39 respectively along the inner flanges, spaced according to the mathematical theory of probability. Channels 17, 18 must be reversed, after disassembling the frame, in order to attach the cords to extend in a series arranged in accordance with the theory of probability, unless the construction of Figs. 10 and 11 is employed. Channels 17, 18 thus permit the user to mark vertical lines equally spaced apart or alternatively "probability" lines; and if desired the frame may be turned 90° to make these lines horizontal instead of vertical.

In Fig. 7 the frame is shown with channels 17, 18 holding tensioned horizontal cords 21a spaced equal distances apart (say 2 in.), also with slightly modified channels 16, 19 turned over to bring the

cords 21 attached thereto outermost and arranged in a double vertical logarithmic series. It is presumed that channels 16, 18 are here modified by locating the double log. series notches on the inside flange, and the single log. series notches on the outside flange, as the flanges are viewed in Fig. 1. As the equally spaced cords are adjacent the blackboard (in the position shown) these may be plucked or snapped to make a series of equally spaced horizontal co-ordinates on the blackboard and then the frame may be turned completely over and held so that the cords in the double logarithmic series are adjacent the blackboard, whereupon a series of vertical lines arranged in a double logarithmic series may be marked on the board in addition to the horizontal co-ordinates. Alternatively, the horizontal lines may be "probability" lines (if channels 17 and 19 are reversed end for end) and the vertical lines are reversed end for end and the vertical lines may be in single logarithmic series.

The described construction with proper manipulation permits the following chalk markings on a blackboard:

1. Lines in a single logarithmic series, extending vertically or horizontally.
2. Lines in double logarithmic series, extending vertically (Fig. 1) or horizontally.
3. Lines equally spaced apart and extending vertically or horizontally (Fig. 7).
4. Lines spaced in conformity with the mathematical theory of probability, and extending vertically or horizontally.
5. Single log. series lines running vertically, and single log. series lines running horizontally.
6. Single log. series lines (either horizontal or vertical) with double log. series (either vertical or horizontal).
7. Double log. series lines arranged vertically with double log. lines arranged horizontally.
8. Single log. series lines (either horizontal or vertical) with equally spaced lines (either vertical or horizontal).
9. Double log. series lines (either horizontal or vertical) with equally spaced lines (either vertical or horizontal). See Fig. 7.
10. Single log. series lines (either horizontal or vertical) with "probability" lines (either vertical or horizontal).
11. Double log. series lines (either horizontal or vertical) with "probability" lines (either vertical or horizontal).
12. Equally spaced lines (either horizontal or vertical) with "probability" lines (either vertical or horizontal).
13. Equally spaced lines arranged both horizontally and vertically.
14. "Probability" lines arranged both horizontally and vertically.

It will be clear that the frame may be held at any angle to the horizontal so that several series of lines may be marked on the board at angles to the vertical or horizontal. Also the invention is not limited to the described line spacing: other spacings of the notches may be resorted to, and other arrangements of the notched channels may be used. While notches have been described and shown as the most convenient means for securing the cords, other means, such as small pins arranged in pairs, could be employed to hold the knots on the cord ends. Various other departures from the described construction and operation may be made if within the scope of the appended claims.

It will be appreciated that as the four corner pieces are readily removable from the channel

members, the device is easily packed into a small space, which is a convenience for storage or shipment.

What I claim is:

1. A device of the character described comprising a rigid frame having a central opening and lying in the same general plane, cord-securing means on the frame spaced at predetermined intervals according to some mathematical law or theory, a plurality of chalk-receiving cords temporarily secured at opposite ends to said cord-securing means and stretched across the opening in the frame, the frame consisting of a plurality of separable sides, means to secure the separable sides together at their ends, said frame being four-sided, each of the sides having cord-securing means in a certain sequence or series, each pair of opposite sides having the same series, the series of one pair of opposite sides differing from the series of the other pair, so that many different sets of parallel and crossing chalk lines may be marked on a blackboard.

2. A device of the character described comprising a rigid rectangular frame having a central opening and lying in the same general plane, cord-securing means on the frame spaced at predetermined intervals according to some mathematical law or theory, a plurality of chalk-receiving cords temporarily secured at opposite ends to said cord-securing means and stretched across the opening in the frame, the frame consisting of four rigid frame members and four corner pieces, each corner piece being insertible partly in the ends of two frame members at right angles to each other, and means to secure each corner piece to the adjacent ends of two of the rigid frame members, the parts being constructed and arranged so that the two outer faces of each corner piece are flush with the respective outer faces of the two frame members which are joined together by the corner piece.

3. A device of the character described, comprising a rigid open frame consisting of a plurality of separable parts and means for securing the separable parts together, the frame being flat so that it may lie flat against a blackboard or other plane surface, said frame having cord-securing means arranged on opposite sides at predetermined intervals according to some mathematical law or theory, and a plurality of chalking cords stretched across the frame opening under tension and temporarily secured by said securing means according to a predetermined plan so as to lie in substantially the same plane; the frame being rectangular and being composed of four channels with four rigid angular corner pieces each of which fits snugly in the ends of two channel members at right angles to each other, the corner pieces being held in the channels wholly by friction.

4. A device of the character described comprising a rigid open frame consisting of four channel members and four corner pieces removably secured to the ends of the channel members at the four corners of the frame, each of the channel members having cord-receiving means spaced along the top edges of both of the flanges of the channel, the spacing of the cord-receiving means being according to some mathematical law or theory, a plurality of cords adapted to be placed in said cord-receiving means and stretched across the opening in the frame, stop means on the ends of the cords and engaging the flange having the cord-receiving means to hold the cords in tension, the bottoms of at least two

of the channels having apertures through which the ends of the cords and the stop means thereon may be passed, said apertures being aligned transversely of the channels with the cord-receiving means on one of the flanges thereof.

5. The invention defined in claim 4, wherein the cord-receiving means are notches extending downwardly from the tops of the flanges, and the apertures are triangular with the apexes of the triangles aligned with the centers of the notches on one of the flanges.

6. Means for securing ends of cords having stop means to a frame having channel members, said means consisting of apertures in the bottom or webs of the channel members and notches formed in the top edges of the flanges of the channels, the parts being so constructed and arranged that there is one aperture for each notch in one of the flanges and the centers of the apertures lie in the same transverse planes as the centers of the corresponding notches, and furthermore the end of each cord may be held by its stop means after the cord is wrapped around the outside of the channel and engaged with a notch on the outside flange or alternatively after the cord and its stop means are passed through an aperture and up inside the channel and the cord is passed through the notch which lies in the same plane as said aperture, with the stop means back of the last mentioned notch.

7. The invention as defined in claim 6, wherein the apertures are each triangular with their apexes directed toward the notches in their transverse planes, the converging walls of the apertures serving to align a cord relative to a notch and also acting to frictionally grip the cord in assembling.

8. A device of the character described comprising a rigid frame having a central opening and lying in the same general plane, cord-securing means on opposite sides of the frame spaced apart in accordance with a single logarithmic series, a plurality of chalk-receiving cords temporarily secured at opposite ends to said cord-securing means and stretched across the opening in the frame, the frame consisting of a plurality of separable sides and means to secure the separable sides together at their ends.

9. A device of the character described comprising a rigid frame having a central opening and lying in the same general plane, cord-securing means on opposite sides of the frame spaced apart in accordance with a double logarithmic series, a plurality of chalk-receiving cords temporarily secured at opposite ends to said cord-securing means and stretched across the opening in the frame, the frame consisting of a plurality of separable sides and means to secure the separable sides together at their ends.

10. A device of the character described comprising a rigid frame having a central opening and lying in the same general plane, cord-securing means on opposite sides of the frame spaced apart in accordance with the mathematical theory of probability, a plurality of chalk-receiving cords temporarily secured at opposite ends to said cord-securing means and stretched across the opening in the frame, the frame consisting of a plurality of separable sides and means to secure the separable sides together at their ends.

11. A device of the character described comprising a rigid rectangular frame having a central opening and lying in the same general plane, cord-securing means spaced in a double logarithmic series along to corresponding edges of the frame on opposite sides and other cord-securing

means spaced in a single logarithmic series along the other two corresponding edges of the frame and on the same two opposite sides, a plurality of chalk-receiving cords temporarily secured at opposite ends to said cord-securing means and stretched across the opening in the frame, the frame consisting of a plurality of separable sides and means to secure the separable sides together at their ends.

12. A device of the character described comprising a rigid rectangular frame having a central opening and lying in the same general plane, cord-securing means spaced in a double logarithmic series along two corresponding edges of the frame on two opposite sides, other cord-securing means spaced in a single logarithmic series along the other two corresponding edges of the frame on the same two opposite sides, other cord-securing means spaced evenly along two corresponding edges of the frame on the other two opposite sides, and still other cord-securing means spaced apart according to the mathematical theory of probability along the last-mentioned opposite sides but along edges differing from those provided with the evenly spaced securing means, a

5 plurality of chalk-receiving cords temporarily secured at opposite ends to said cord-securing means and stretched across the opening in the frame, the frame consisting of a plurality of separable sides and means to secure the separable sides together at their ends.

PAUL E. WHITTINGTON.
